UNITED STATES PATENT OFFICE.

ENOCH L. TAYLOR, OF PHILADELPHIA, PENNSYLVANIA, ASSIGNOR OF ONE-HALF TO HENRY WOOD, OF SAME PLACE.

RAILROAD-RAIL GUARD AND SUPPORT.

SPECIFICATION forming part of Letters Patent No. 544,137, dated August 6, 1895.

Application filed December 14, 1894. Serial No. 531,847. (No model.)

To all whom it may concern:

Be it known that I, ENOCH LEWIS TAYLOR, a citizen of the United States, residing in the city and county of Philadelphia, State of Pennsylvania, have invented a new and useful Improvement in Railroad-Rail Supports, Fastenings, and Guards, which improvement is fully set forth in the following specification and accompanying drawings.

10 My invention consists of a novel rail support and fastening more particularly adapted for bridges, elevated roads, &c., the same being of firm and durable construction and adapted to hold the rail in a powerful manner, and to be tightened or driven up as the parts wear off.

It also consists of a guard for the rail of novel and strong construction, as will be hereinafter set forth.

20 Figure 1 represents a partial end elevation and partial vertical section of a rail support and guard embodying my invention. Fig. 2 represents a top or plan view thereof. Fig. 3 represents a perspective view of a chair and adjacent portion of a beam embodying my invention. Fig. 4 represents an end view of said beam.

Similar letters of reference indicate corresponding parts in the several figures.

30 Referring to the drawings, A designates a column, on the top B of which is supported the chair C, which consists of the bed-plate D and the vertical limbs E depending therefrom, one of said limbs having an inwardly-projecting flange F at the base thereof. Rising from the bed D is a cheek-piece G, which is adapted to embrace one of the flanges of the rail. A portion of the bed D is cut away, forming a transversely-extending recess H, in 35 which is seated the portion J of the double L or Z shaped beam K, which portion rests on the side limbs E of the chair C, and is formed with a cheek-piece L, which is diagonally opposite to the cheek-piece G, so as to embrace the respective flange of the rail, it being noticed that the rail rests partly on the portion J of the beam K, and said bed and portion J rest on the top B of the column A, whereby the rail is firmly supported. The beam K is 45 sustained on the floor or other suitable portion of the bridge, road, &c. It will also be

noticed that the vertical and lower limbs of the beam K are cut away so as to admit the chair C between them, while the portion J, which is part of the upper limb of said beam, 55 enters the recess H of the bed D, and rests on the limbs E thereof, as has been stated.

Depending from opposite sides of the top B are angle-bars M and N, which are bolted to the top B, the bars N resting on the flange 60 F and the bar M being engaged by a screw P, which is fitted to the adjacent side limb E of the chair and adapted to tighten against said bar M, by which provision the chair may be driven up, in the present case to the left, 65 whereby the cheek-piece G is tightened against the contiguous flange of the rail, while the opposite flange is tightened against the cheek-piece L, thus firmly retaining the rail in position. 70

K designates guards, which are formed of metal crimped upwardly, producing the side legs Q, and having the flat central portion Q' and the outwardly-projecting feet Q² at the bases of the outer sides of said legs. The central portion Q rests on the top of the chair and portion J of the beam, and the feet Q², while also sustaining the guard, receive the bolts by which the guard is secured to the top E of the column and the angle-bars M and N, 75 80 the guard thus being firmly supported.

The guard is cut away at places where the cheek-pieces exist to allow the latter to pass through the guard and engage the flange of the rail. 85

Having thus described my invention, what I claim as new, and desire to secure by Letters Patent, is—

1. A support, a chair having a cheek piece connected therewith, depending limbs on said chair, angle bars secured to said support, and mechanism connected with said chair bearing against one of said angle bars for adjusting said chair, substantially as described. 90

2. A rail guard formed of a piece of metal having elevated side portions, a central portion adapted to have a rail seated thereon, and means for securing it to a support, said central portion joining the inner limbs of said side portions, substantially as described. 95 100

3. A column having a top, an angle bar connected with said top, a chair with a depend-

ing limb, and a flange on the lower end of the latter, the bar being seated on said flange, the parts named being combined substantially as described.

5 4. A column having a top, an angle bar connected with said top, a chair with a depending limb, and a screw which is fitted to said limb and adapted to bear against said bar, the parts named being combined substantially as described.

5 5. A chair, a beam part of which is seated on said chair, a support for the seat and part, angle bars connected with said support, a flange on one of the limbs of said chair on which one of said bars is sustained, and a screw on the opposite limb engaging the other angle bar, said parts being combined substantially as described.

15 6. A rail guard formed of a single piece of metal, having upwardly crimped side portions

a flat central portion adapted to have a rail seated thereon, and feet for securing the guard to the rail support, substantially as described.

7. A rail-supporting beam and rail-supporting column, in combination with a chair, and a rail guard the side portions of which are elevated, and the central portion rests on said chair and has the rail superimposed thereupon, the parts being combined substantially as described.

8. A rail guard formed of elevated side portions, a flat central portion, supporting and securing feet on said side portions, and cut away portions to admit the projections of cheek pieces, substantially as described.

ENOCH L. TAYLOR.
